Primary Examiner — Paula Allen Greene

(74) Attorney, Agent, or Firm — Ziegler IP Law Group,
LLC(57) **CLAIM**

The ornamental design for an earphone, as shown and described.

DESCRIPTION

FIG. 1 is a perspective view of an earphone showing the new design.

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a right side view of FIG. 1; and,

FIG. 7 is a left side view of FIG. 1.

The environmental structure shown with broken lines in the drawings forms no part of the claimed design.

1 Claim, 7 Drawing Sheets(56)
